CIRCUIT BREAKER CONTROL SYSTEM

Arnold Haller, Baden, Switzerland, assignor to
 Aktiengesellschaft Brown, Boveri & Cie., Baden,
 Switzerland

Application September 11, 1944, Serial No. 553,632
 In Switzerland September 11, 1943

14 Claims. (Cl. 200—82)

1

The control system of a pneumatically operated circuit breaker has to transmit switching orders of all kinds to the actuating elements of the moveable switch contacts. The switching movements must always be clear and complete, quite independently of the fact whether the orders are short or long, contradict each other, occur in rapid succession, or are merely a repetition of some orders which have already been executed.

The object of the present invention is to provide a control system for a pneumatically operated electric circuit breaker where all the aforementioned conditions can be readily fulfilled. According to the invention this is achieved due to the control valves both for the closing and opening order being actuated by power storage devices whose charging organs are controlled by the moveable contact of the circuit breaker.

A constructional example of the invention is illustrated diagrammatically in the accompanying drawing where Fig. 1 shows a circuit breaker, the pneumatic drive and control being shown in longitudinal section. Fig. 2 shows the control system during the opening or circuit-breaking process.

The essential elements required for the control and switching operations of the circuit breaker are shown in Fig. 1. The moveable switch blade 1 of the circuit breaker is controlled in its end position "in" and "out" by supplying compressed air to one or the other side of the piston 2. For this purpose compressed air is supplied from container 3 over valve 4 or 4' and pipe 5 or 5' respectively to the working cylinder 6. Valves 4, 4' which are moved by levers 7, 7' respectively are actuated by power storage devices which in this case consist of toggle levers 8, 8' and springs 9, 9'. In Fig. 1 the circuit breaker is shown in the closed position. The left-hand power storage device which serves to open the circuit breaker is thus held by catch 10 in the extended position, whilst the right-hand power storage device for the "closing" orders is kept extended by its holding catch 10' and furthermore by the charging cam 11'. The left-hand storage device is also provided with a corresponding charging cam 11, both cams 11, 11' being actuated from the switch blade 1 by way of shaft 12 and link 13. Holding catches 10, 10' engage release catches 14 and 14' respectively, and Fig. 1 shows how commanding impulses are transmitted by various command elements so as to cause a vertical movement of these release catches 14, 14'. The commanding

2

elements consist for instance of press-buttons 15 and 15' which are at the same time constructed as the cores of remote-controlled magnets 16 and 16', a second remote-controlled magnet 17 serving for switching-out purposes and a low-voltage magnet 18 which causes an interruption when the coil is not excited, also being provided. A locking magnet 23 is also provided, which by lifting the release catch 14' can prevent the transmission of a switching order, when this is desired in connection with a change in voltage in an electrical circuit. These commanding elements 15 to 18 and 23 together with the associated control gear are all located on a common frame 24 which is shown by broken lines and indicates the most expedient arrangement of these elements in a control block. A further commanding element located outside the control block is provided in the form of an over-current relay 19 which also actuates the release catch 14 by means of a link 20.

In order to be able to block operation of the circuit breaker under certain circumstances which are referred to in greater detail later on, a rod 21 is provided which is actuated by lever 7 or 7' and causes the release catches 14 and 14' respectively to disengage the holding catches 10, 10'. Blocking rod 21 is also actuated by a pressure measuring device 22, which when the pressure in container 3 drops below a certain minimum value operates and also blocks the control.

The method of operation of the control arrangement is as follows:

Commencing with the circuit breaker in the position shown in Fig. 1, when a switching-out order is transmitted by one of the commanding elements 15, 16, 17 or 18, the left-hand power storage device 8, 9 is released due to the vertical movement of the release catch 14 and the rocking of the holding catch 10; toggle lever 8 bends upwards and spring 9 opens valve 4 by means of lever 7. This action is illustrated in Fig. 2. At the same time lever 7 has moved rod 21 to the left so that release catches 14, 14' are disengaged from the holding catches 10, 10' of both power storage devices. It is thus clear that once the switching-out operation has been initiated it cannot be influenced by external means, that is neither by prematurely interrupting the switching order nor by a counter-order to switch in with catch 14'. Release catches 14, 14' only come into engagement again with holding catches 10, 10' when upon completion of the switching-out order, circuit breaker switch blade 1 by means of link 13 and shaft 12 has rotated charg-

ing cam 11, whereupon the left-hand power storage device 8, 9 becomes recharged and valve 4 closed. At the same time charging cam 11' which is mounted on shaft 12 is also rotated so that the right-hand power storage device is ready to execute a switching-out order.

The switching-in operation which can be initiated by the commanding elements 15' or 16' only after the breaker has moved to full open position, the valve 4 has reclosed, and release catch 14' returned to engagement with its associated holding catch 10' by movement in the opposite direction of rod 21, is performed in a similar manner to the switching-out operation just described and does not require any further explanation. It only requires to be emphasized that also a switching-in operation, once it has commenced, cannot be influenced by any further switching orders until the circuit breaker has fully completed its closing operation.

I claim:

1. In a circuit interrupter, the combination with a movable switch blade, a power cylinder and piston for moving said switch blade into and out of engagement with a cooperating switch element, a source of pressure gas, and independently operable valves for controlling communication between said pressure gas source and the respective ends of said power cylinder; of means including individual power devices for opening the respective valves, means mechanically connected to and operable with said switch blade for storing power in said power devices, and means selectively operable to release one or the other of said power devices for movement to open the associated valve, thereby to admit pressure gas to an end of said power cylinder for a movement of the switch blade in one direction.

2. In a circuit interrupter, the invention as recited in claim 1, in combination with means mechanically connecting said power devices and operated by the initial release movement of one power device to prevent a release of the second power device prior to the completion of the switch blade movement resulting from said release of the first power device.

3. In a circuit interrupter, the invention as recited in claim 1 wherein said means for storing power in said power devices comprises means operable near the end of the movement of the switch blade in either direction by said piston to store power in the power device that was released to open the valve that initiated the piston movement.

4. In a circuit interrupter, the invention as recited in claim 1 wherein said means for storing power in said power devices includes means operable when said switch blade is in either end position to prevent a release of the power device of the control valve that was last opened to effect movement of the switch blade into that end position.

5. In a circuit interrupter, the invention as recited in claim 1 wherein said power devices are spring-loaded toggle levers.

6. In a circuit interrupter, the invention as recited in claim 1, in combination with means responsive to decreased pressure of said pressure gas source to prevent release of said power devices.

7. In a circuit interrupter, the combination with a jaw contact, a switch blade, a power

cylinder and piston for moving said switch blade into and out of engagement with said jaw contact, a source of pressure gas, passage means including valves for connecting said pressure gas

5 source selectively to the respective ends of said power cylinder to effect movement of said switch blade in opposite directions, of means for controlling the operation of said valves; said valve controlling means comprising spring means for 10 actuating the respective valves, means actuated by movement of the switch blade in one direction to stress the spring means of the valve that was opened to effect movement of the switch blade in that direction, means automatically latching the stressed spring means to prevent its operation of the associated valve, and means for unlatching said stressed spring means of the pair of valves.

8. In a circuit interrupter, the invention as 20 recited in claim 7 wherein said unlatching means is manually actuated.

9. In a circuit interrupter, the invention as recited in claim 7 wherein said unlatching means is actuated by relay means responsive to the 25 current through the circuit interrupter.

10. In a circuit interrupter, the invention as recited in claim 7 wherein said unlatching means is controlled by the pressure of the gas within 30 said pressure gas source.

11. In a circuit interrupter, the invention as recited in claim 7, wherein said means for stressing a spring means blocks actuation of the associated valve by that spring means prior to an opening of the other valve by an unlatching of 35 its spring means.

12. In a circuit interrupter, the invention as recited in claim 7 wherein said spring means comprise spring loaded toggle mechanisms.

13. In a circuit interrupter, the invention as 40 recited in claim 7 wherein said spring means comprise spring loaded toggle mechanisms; and said latching means comprises a holding catch for retaining the associated toggle mechanism in spring-stressed condition.

14. In a circuit breaker including a power cylinder and a piston for actuating a movable contact into and out of engagement with a stationary contact, a source of pressure gas, valves 45 controlling the flow of pressure gas to the opposite ends of said cylinder, power devices for opening the respective valves, means actuated in response to operation of the circuit breaker contacts for storing power in said power devices, means selectively operable to release each of said

50 power devices to open or close said contacts, and interlock means actuated upon release of one of said power devices to prevent release of the second power device prior to completion of the opening or closing operation of the circuit breaker contacts resulting from the release of said first power device.
